FLYING SAUCER PULL TOY

Nilson V. Ortiz, San Francisco, Calif., assignor to
Niltec Corporation, San Francisco, Calif.

Filed Oct. 15, 1974, Ser. No. 514,854

Term of patent 14 years

Int. Cl. D21—01

U.S. Cl. D34—15 D

FIG. 1 is a top plan view of a flying saucer pull toy embodying my new design;

FIG. 2 is a side elevational view of FIG. 1, the view from the opposite side being a mirror image thereof;

FIG. 3 is a front elevational view thereof;

FIG. 4 is a rear elevational view thereof; and

FIG. 5 is a bottom plan view thereof.

I claim:

The ornamental design for a flying saucer pull toy, as shown and described.
